(57) **CLAIM**

The ornamental design for a wireless charger stand, as shown and described.

DESCRIPTION

FIG. 1 is a perspective view of the wireless charger stand showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view of thereof;

FIG. 7 is a bottom plan view of thereof;

FIG. 8 is a perspective view of the wireless charger stand in a closed configuration;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view of thereof; and,

FIG. 14 is a bottom plan view of thereof.

1 Claim, 14 Drawing Sheets
